UNITED STATES PATENT OFFICE

2,542,949

CARTON AND EASEL FOR SHEETS

John Dickinson Schneider, Deerfield, Ill.

Application June 15, 1948, Serial No. 33,037

6 Claims. (Cl. 40—102)

1

This invention relates to a carton and easel for sheets and more particularly to apparatus adapted to be assembled as a transporting carton or as a display easel for sheets having displays thereon.

One feature of this invention is that it provides an improved transporting carton and display easel for sheets having displays thereon; another feature of this invention that it provides a backing member having a pair of oppositely disposed side flaps hingedly mounted along opposite side edges thereof, said flaps being adapted to form a support to maintain said backing member upright at an angle to the vertical; another feature of this invention is that the side flaps are each provided with a lower bendable portion, preferably triangular in form, which may be bent to form a base portion, thereby supporting said backing member in an upright position at an angle from the vertical; an additional feature of this invention is that it provides a bottom flap hingedly mounted on said backing member and adapted to be secured to the bendable portion of each of said side flaps to provide a very stable easel; a further feature of this invention is that the display sheets are mounted on a hanger flap hingedly secured to the backing member and are completely enclosed within the carton formed by the apparatus for transportation, the hanger flaps and sheets being adapted to be swung through an angle of approximately 180° to present the display on said sheets from the opposite side of said backing member when the apparatus is assembled as an easel; still another feature of this invention is that two oppositely disposed flaps (the side flaps as illustrated) have a combined width at least equal to the width of the backing member, said flaps preferably being each of the order of one-half the width of said backing member so that when said flaps are swung to overlie said backing member the flaps completely cover a side of said member; yet a further feature of this invention is that the hinged connection between the side flaps and the backing member is designed so that said flaps form a support for the backing member when the flaps are swung less than 90° from said backing member, thereby providing an easel wherein the side flaps are not visible from the front; and still an additional feature of this invention is that the display sheet and hanger flap may be fastened to the backing member to insure that the sheets retain a desirable display position.

Other features and advantages of this inven-

2

tion will be apparent from the following specification and from the drawings in which:

Fig. 1 is a perspective view of apparatus constructed in accordance with the present invention, said apparatus being assembled as a carton;

Fig. 2 is an enlarged perspective view of the apparatus of Fig. 1 assembled as an easel;

Fig. 3 is a reduced perspective view of the apparatus of Fig. 1 in the process of being disassembled as a carton and assembled as an easel;

Fig. 4 is a fragmentary perspective view of the upper portion of the apparatus assembled as an easel;

Fig. 5 is a perspective view of the apparatus in process of assembly as an easel looking from the back thereof;

Fig. 6 is a fragmentary perspective view of the back of the apparatus showing the connection between the bottom flap and the bendable portion of the side flaps;

Fig. 7 is a perspective view of the apparatus assembled as an easel looking from the back thereof;

Fig. 8 is an enlarged fragmentary vertical section along the line 8—8 of Fig. 2; and

Fig. 9 is an enlarged fragmentary vertical section along the line 9—9 of Fig. 2.

Referring more particularly to the drawings, the apparatus comprises a backing member 10 which preferably is formed of corrugated fiber board. A pair of oppositely disposed side flaps 11 and 12 are hingedly mounted along opposite side edges of the backing member 10 and extend along substantially the entire length of said edges as shown in Figs. 1, 2 and 3. These flaps have a combined width at least equal to the width of the backing member and preferably each side flap has a width of the order of one-half the width of the backing member so that the edges of the flaps are substantially in abutment and said flaps completely cover a side of the backing member when the flaps are swung to overlie the backing member as shown in Fig. 1. The hinge mounting may be of the type which is conventional in forming boxes and cartons of corrugated fiber board, here being shown as comprising a double fold 13a and 13b, these folds being spaced to provide a space between backing boards and the side flaps when the side flaps are swung to overlie the board. The width of the spacing between the folds 13a and 13b will, of course, determine the depth of the carton, and in a carton intended to contain 10 or a dozen display sheets a spacing of about $\frac{3}{4}$ of an inch or an inch between the folds 13a and 13b will suffice. While

shown as being integral, obviously, if desired the backing members and the flaps may be made of separate pieces and hinged together with tape or similar fastening means.

Each flap has a lower portion 11a and 12a, respectively, which is bendable, this portion preferably being defined by score lines as shown at 11b and 12b in Fig. 1, the portions 11a and 12a each preferably being in the form of a triangle having its relatively short base extending from the lower corner of the respective side flap along the outer edge of said flap opposite said hinge mounting, said triangle having its apex at the lower corner of the respective side flap adjacent the point of connection of the side flap with the backing member 10.

A bottom flap 14 is hingedly mounted along the bottom edge of said backing member and extends along substantially the entire length of said bottom edge as shown best in Fig. 6. The bottom flap 14 is hinged similarly to the side flaps 11 and 12 and is adapted to cover the lower portion of the side of the backing member when the bottom flap is swung to overlie said backing member.

A hanger flap 15, preferably similar in size and shape to the bottom flaps 14, is hingedly mounted along the top edge of the backing member 10 and extends along substantially the entire length of said top edge as shown best in Fig. 3. The hanger flap covers the upper portion of the side of the backing member when in a first position where said flap is swung to overlie said backing member. Obviously if desired the hanger flap and bottom flap could be formed with a combined width at least equal to the width of the backing member and the side flaps could each be shortened so they are not in abutment when said side flaps are swung to overlie the backing member.

A plurality of display sheets 16 are mounted on the hanger flap 15 adjacent the top edge of the backing member 10 by means of pins or rivets 17 and 18. When the apparatus is assembled as a carton the display sheets 16 will lie between the hanger flap 15 and the bottom flap 14 on the backside of said sheets and the backing member 10 on the front or display side of said sheets as will be apparent from a consideration of Figures 1, 2 and 3, and said hanger flap 15 and sheets 16 are adapted to be swung from this first position through an angle of approximately 180 degrees to a second position illustrated in Figs. 2 and 4 wherein the display on said sheets is presented from the side of the backing member 10 opposite the side of said member from which the side flaps 11 and 12 extend, said sheets being supported by said hanger flap 15 and backing member 10 when in said second position.

In Fig. 1 the apparatus is illustrated assembled as a carton with the display sheets 16 inside the carton. If desired the carton may be sealed by means of a tape 20 bridging the abutting edges of the side flaps 11 and 12. As is conventional in assembling a carton the hanger flap 15 and the bottom flap 14, which in the embodiment illustrated are not of sufficient length to abut each other, are folded inside the side flaps 11 and 12, the hinge mounting of said hanger and bottom flaps providing the ends of the carton.

In Fig. 2 the apparatus has been disassembled as a carton and assembled as an easel, Figs. 3-7 showing the means by which this operation is performed. After the tape 20 has been cut or removed the side flaps 11 and 12 and bottom flap

14 are swung away from the backing member 10 to permit the hanger flap 15 and the sheets 16 to be swung away from said backing member as illustrated in Fig. 3, and as shown in Fig. 4 said hanger flap and sheets are swung through an angle of approximately 180 degrees to present the display on said sheets from the side of the backing member opposite the side from which the side flaps 11 and 12 extend, said sheets resting against the back of the member 10 and being supported by the hanger flap and said member 10.

The sheets 16, hanger flap 15 and backing member 10 are provided with a hole shown at 21 in Figs. 4 and 7, and a rivet 22 is passed through this hole and acts to secure the sheets and hanger flap to the backing member 10 as shown in Fig. 9. Since the rivets 17, 18 and 22 are approximately in a straight line adjacent the upper edge of the hanger flap, as each sheet is used it may be merely turned over to the inside or back of the apparatus and the next succeeding sheet will be in display position.

After the hanger flaps and sheets have been inverted from their closed position to their display position the bendable portion of each side flap is bent inwardly, approximately at a right angle. If desired this operation may be facilitated by the use of a straight edge, as the ruler 23 shown in Fig. 5. Push pins 25 and 26 or other fastening devices, as rivets, may then be utilized to secure the bottom flap 14 to the bendable portions 11a and 12a of the side flaps, this arrangement providing a sturdy support to hold the backing member 10 in an upright position, and proper balance is assured since the backing member is supported at an angle to the vertical, sloping rearwardly as best seen in Fig. 7, so that said member cannot fall forwardly even though its supporting means are located to the rear. The slope towards the rear is, of course, caused by bending the triangular portions 11a and 11b away from the vertical supporting portion of the side flaps 11 and 12.

I prefer to provide rivet 22 and push pins 25 and 26 in an envelope inside the carton when it is shipped, and if desired this envelope may contain directions for assembling the apparatus as an easel.

Since it is not necessary to cut or tear the apparatus in assembling it either as a carton or as an easel, if desired the easel may be disassembled by removing the push pins 25 and 26 and the rivet 22, swinging the hanger flap 15 and sheets 16 through approximately 180 degrees where they rest against the other side of the backing member 10, straightening out the bendable portions 11a and 12a and swinging the bottom flap 14 and the side flaps 11 and 12 to overlie the backing member. Obviously the apparatus may be used as many times as desired for displays or lectures.

The formation of the bendable portions 11a and 12a as illustrated results in an easel in which the backing member 10 is supported in an upright position a few degrees from the vertical, and since the hinged connection of the side flaps results in a space between the folds 13a and 13b, the side flaps are swung less than 90 degrees away from their closed position of Fig. 1 to their open or easel forming position of Fig. 2. Consequently the side flaps cannot be seen by an observer in front of the display.

While I have shown and described certain embodiments of my invention it is to be understood that it is capable of many modifications, changes, therefore, in the construction and ar-

angement may be made without departing from the spirit and scope of the invention as disclosed in the appended claims.

I claim:

1. Apparatus of the character described, comprising: a backing member adapted to support at least one display sheet; and a pair of oppositely disposed side flaps hingedly mounted along opposite side edges of said backing member, said flaps being contained within projections of the top and bottom edges of said backing member, and said flaps each having a lower edge portion which is readily bendable to form a base portion, said flaps forming a portion of a carton when swung to overlie said backing member, and said flaps being adapted when swung away from said backing member to form a support to maintain said backing member upright at an angle to the vertical.

2. Apparatus of the character claimed in claim 1, wherein the bendable portion of each side flap is in the form of a triangle having its base extending from the lower corner of said side flap along the outer edge of said flap opposite said hinge mounting, and having its apex at the lower corner of said side flap adjacent said backing member.

3. Apparatus of the character described, comprising: a backing member adapted to support a plurality of display sheets; a pair of oppositely disposed side flaps hingedly mounted along opposite side edges of said backing member, said flaps each having a lower triangular edge portion which is readily bendable to form a base portion, said flaps forming a portion of a carton when swung to overlie said backing member, and said flaps being adapted when swung away from said backing member to form a support to maintain said backing member upright at an angle to the vertical; a bottom flap hingedly mounted along the bottom edge of said backing member; and readily removable means for securing said bottom flap to said bendable portions to form said base portion.

4. Apparatus of the character described, comprising: a backing member; a pair of oppositely disposed side flaps hingedly mounted along opposite side edges of said backing member, said flaps each having a score line defining a lower triangular portion which is bendable to form a base portion, said flaps forming a portion of a carton when swung to overlie said backing member, and said flaps being adapted when swung away from said backing member to form a support to maintain said backing member upright at an angle to the vertical; a bottom flap hingedly mounted along the bottom edge of said backing member; readily removable means for securing said bottom flap to said bendable portions to form said base portion; and a hanger flap hingedly mounted along the top edge of said backing member, said hanger flap being adapted to have a plurality of display sheets mounted thereon.

5. Apparatus of the character described, comprising: a backing member; a pair of oppositely disposed side flaps having a length equal to the length of the backing member and being hingedly

mounted along opposite side edges of said backing member and extending along substantially the entire length of said edges, said flaps each having a lower portion which is bendable to form a base portion, and said flaps being adapted to form a support to maintain said backing member upright at an angle to the vertical when said flaps are swung approximately 90 degrees from said backing member; a bottom flap hingedly mounted along the bottom edge of said backing member and extending along substantially the entire length of said bottom edge, said bottom flap being adapted to cover the lower portion of said side of said backing member when swung to overlie said member and being adapted to be swung through an angle of less than 90 degrees from said backing member and be secured to the bendable portion of said side flaps; and a hanger flap hingedly mounted along the top edge of said backing member, said hanger flap being adapted to have at least one display sheet mounted thereon, two oppositely disposed flaps having a combined width at least equal to the width of said backing member and being adapted completely to cover a side of said backing member when said flaps are swung to overlie said backing member.

6. Apparatus of the character described, comprising: a backing member; a pair of oppositely disposed side flaps hingedly mounted along opposite side edges of said backing member and extending along substantially the entire length of said edges, said flaps each having a lower triangular portion which is bendable to form a base portion, said flaps forming a portion of a carton when swung to overlie said backing member, and said flaps being adapted when swung away from said backing member to form a support to maintain said backing member upright at an angle to the vertical; a hanger flap hingedly mounted along the top edge of said backing member and extending along substantially the entire length of said top edge, said hanger flap covering the upper portion of a side of said backing member when in a first position; and a plurality of display sheets mounted on said hanger flap adjacent the top edge of said backing member, said hanger flap and sheets being adapted to be swung through an angle of approximately 180 degrees to a second position to present the display on said sheets from the side of said backing member opposite the side from which said side flaps extend, said sheets being supported by said hanger flap and backing member when in said second position.
